CLAIM

The ornamental design for a snowmobile side panel, as shown and described.

DESCRIPTION

FIG. 1 is a rear right perspective view showing a snowmobile side panel according to my design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

Throughout the Figures, broken lines showing structure are for illustrative purposes only and form no part of the claimed design.
